UNITED STATES PATENT OFFICE.

WILLIAM HOWELL ONION, OF NEW ORLEANS, LOUISIANA.

CONVEYER.

Application filed June 22, 1922. Serial No. 570,154.

To all whom it may concern:

Be it known that I, WILLIAM HOWELL ONION, a citizen of the United States, and a resident of New Orleans, in the parish of Orleans and State of Louisiana, have invented certain new and useful Improvements in Conveyers, of which the following is a specification.

This invention relates to a conveyer.

10 The invention more particularly relates to a conveyer of the endless belt type and has for its purpose to provide a conveyer of this character which is adapted to be utilized for handling heavy or light articles with equal 15 efficiency, which is comparatively inexpensive to install, which is durable and consisting of few numbered parts and which is adapted to operate in a smooth manner for transporting articles, and with a minimum 20 amount of friction of the movable parts.

Other objects and objects relating to details of construction will hereinafter appear in the detailed description to follow.

The invention is illustrated by way of 25 example in the accompanying drawings, in which,

Figure 1 is a top plan view of the conveyer unit constructed in accordance with the present invention.

30 Figure 2 is a view in side elevation of the same, taken with the supporting frame partially excluded.

Figure 3 is a transverse sectional view of the conveyer unit.

35 Figure 4 is a detailed view in elevation illustrating the manner in which the supporting cross bars are secured to the belt.

Figure 5 is a group view illustrating the elements employed for securing the belt to 40 each of the cross bars, and

Figure 6 is a detailed sectional view further illustrating the manner of securing the belt to the different cross bars.

Referring to the drawings more particularly, F indicates generally a supporting frame which consists in the two side walls W properly supported by the posts or legs 10. The side walls are tied together by cross members 11 and by the diagonal members 12, said members 12 being secured to angle irons 13 which are carried by the side walls W. The frame as a whole is rigid and the same may correspond to the dictates of the manufacturer, that is, no specific construction is required.

At each end of the frame there is supported between the side walls W a drum or roller D, said drums in each instance being suitably supported by a rotatable shaft 14 and being of the diameter illustrated in 60 Figure 2. Each drum has its periphery formed with a plurality of radial grooves or recesses 22', said recesses extending the entire length of the drum and for a purpose which will later be described. Over the 65 drums D there passes belt B which should be made of flexible material such as leather or the like and which need not be of the thickness usually employed in a conveyer of this type due to the peculiar construction of the 70 conveyer as will later appear.

For supporting the load on the belt B there is provided a plurality of cross members or axles A, each cross member or axle consisting in a horizontal offset portion 14 75 and the two angular end portions 15, each of which terminates in a spindle 16. Upon each spindle 16 there is journaled a roller R, said roller in each instance having a flange formed upon its inner edge as at 17. 80

To each side wall W there is secured an upper track section T and a lower track section T'. Each section is L-shaped in cross section and secured to the associated wall W so that the portion 20 thereof will be disposed in a horizontal plane and adapted to serve as a track for the associated roller R. The upper track section T in each instance terminates at each end in a semi-circular portion 21 and each semi-circular portion terminates at a point directly above the similar end of the associated track section T' as at 22 (Figure 2). The track section T' in each instance is substantially straight with the exception that its one 90 end terminates in a downwardly curved portion 23. The space existing between the terminals of the track sections T and T' in each instance is sufficient to permit the passage of the rollers R. 100

The belt B is preferably secured to the cross members A in such a manner that the belt will lie upon the upper surface of these cross members as illustrated in Figure 3, that is the portion of the belt carrying the load will so lie while the portion of the belt disposed below the load will bulge downwardly and away from the cross supports A as likewise illustrated in Figure 3. The belt is secured to each cross support at 110

a point adjacent each of its longitudinal edges. One edge of the belt is permanently secured to the cross supports A by bolts or the like as indicated at 24; the other edge, 5 however, is adjustably secured, that is the secured means permit adjustable transverse tensioning of the belt. For making these last named connections between the belt and the cross member A there is provided 10 in each instance a bolt 25 which extends through an elongated slot 26 in the associated cross member A and which also extends through the belt B.

The bolt 25 carries a nut 27 on its one end 15 and also carries a washer 28 adapted to prevent its head from passing through the slot 26. Upon the inner side of the belt B there is positioned a plate 29 having teeth 30 projecting inwardly of the belt and provided 20 with an opening for receiving the bolt 25. Also for the upper side of the belt there is provided a similar plate member 31 through which the bolt 25 extends. The plate 31 is provided with teeth similar to the teeth 25 on the plate 29, as at 31' and is preferably 25 of greater dimensions than the plate 29. The bolt 25 within slot 26 is enlarged as at 30 25' to provide a shoulder against which the plate clip 29 may abut. As is obvious the bolt 25 in each instance has free sliding movement within the slot 26.

The shaft 14 of one of the drums D has its one end extended through the associated side wall W of the frame F and this extended portion of the shaft has secured thereto a cog wheel 32. From the same side wall W there is extended a stud shaft carrying a cog wheel 33 and a fly wheel 34, the cog wheel 33 being in constant mesh with 40 the cog wheel 32.

Upon the same side wall there is also mounted a pass plate 35 to which there is secured a cylinder C, said cylinder having a piston P from which there extends the piston rod P', said rod passing through a suitable stationary guide member G. The piston P' is connected to the fly wheel 34 through the crank rod K. Any suitable motive power such as steam, electricity or compressed air may be utilized for driving the piston P and thus in turn to rotate the drum D associated with the cog wheel 32.

The operation of the present conveyer is as follows:

Articles or material to be transported or moved are deposited upon the belt B in the usual manner. Any suitable means for placing the material or articles upon the belt B may of course be utilized. Upon 55 starting the motive means described the belt B will be caused to move preferably in the direction of the arrow shown in Figure 1 in the drawings. The rollers R upon the track sections T will move thereover and serve to 60 support the entire weight of the load. The

function of the drums D will be merely to cause the belt to move and thus reducing the friction between the drums D and belt B to a minimum whereby to increase the life of the belt. The cross supports A together with the rollers R receive the load upon the belt B and these cross supports should be provided in sufficient numbers so that no sagging of the belt would occur. The rollers R are free to pass from the upper track sections T to the lower track sections T' in the manner illustrated in Figure 2 of the drawings and the cross members A when passing over the drums D may extend into the recesses 22' in said drums. 70 80

It also should be mentioned that with a conveyer constructed in accordance with this invention the belt may run at any desired speed without danger of the rollers leaving the track sections. Also due to the belt being supported by these rollers and cross bars at all times the same travels smoothly and every danger of dislodging of the load being carried is obviated. 85

While I have herein shown and described the preferred form of my invention I wish it to be understood that I am aware of the fact that the construction, combination and arrangement of parts may be changed by those skilled in the art without departing from the spirit of the invention as indicated by the appended claims. 95

What I claim is:

1. In combination, a pair of rollers, an endless belt passing thereover and adapted to move with the rotation of said rollers, a plurality of cross members, each cross member having a central offset, said members being disposed upon the inner side of the belt, means for securing said belt along its longitudinal edges to said cross members, and means for supporting said cross members whereby they may move with said belt. 100 105

2. In combination, a pair of rollers, an endless belt passing thereover and adapted to move with the rotation of said rollers, a plurality of cross members, each cross member having a central offset, said members being disposed upon the inner side of the belt, means for securing said belt along its longitudinal edges to said cross members, means for supporting said cross members whereby they may move with said belt, and power means for rotating one of said rollers. 110 115

3. In combination, a pair of rollers, an endless belt passing thereover and adapted to move with the rotation of said rollers, a plurality of cross members, each cross member having a central offset, said members being disposed upon the inner side of the belt, means for securing said belt along its longitudinal edges to said cross members, means for supporting said cross members whereby they may move with said belt, and adjustable means whereby the belt may be 120 125 130

tensioned transversely upon said cross members.

4. In a device of the character described, a belt, an axle, a roller carried upon each 5 end of the axle, tracks for supporting said rollers, said axle having an intermediate offset portion, and means for securing each edge of the belt to the ends of said axle.

5. In a device of the character described, 10 a belt, an axle, a roller carried upon each end of the axle, tracks for supporting said rollers, said axle having an intermediate offset portion, and adjustable means whereby the belt may be tensioned with relation to 15 the axle.

6. In a device of the character described, a belt, a cross member for said belt having an offset intermediate portion, roller means for supporting the ends of said cross member,

means whereby the one edge of said belt 20 may be rigidly secured to the cross member, and means for loosely securing the other edge of said belt to the other end of said cross member.

7. In a device of the character described, 25 a belt, a cross member for said belt having an offset intermediate portion, roller means for supporting the ends of said cross member, means whereby the one edge of said belt may be rigidly secured to the cross mem- 30 ber, and bolt and clamp means secured to the other edge of the belt, said bolt extending through an elongated slot in the cross member and adapted to have a limited lon- 35 gitudinal movement with respect to the cross member for the purpose described.

WILLIAM HOWELL ONION.
